FOLDING LEG STRUCTURE FOR ARTICLES
OF FURNITURE

Charles Schneider, Los Angeles, Calif.

Application June 9, 1950, Serial No. 167,043

3 Claims. (Cl. 155—165)

1

This invention relates to an improved furniture construction. In particular, this invention relates to an automatic, collapsible and extensible self-actuating supporting device for use with an auxiliary article of furniture which is arranged to be swung from a concealed position within an associated article of furniture into extended relation therewith to provide a leg rest, such as an ottoman, with respect to a chair.

Prior devices include various supporting assemblies for positioning such a concealed auxiliary article for furniture into useable relationship with a chair or davenport. The construction of these prior devices usually included diagonal braces extending from an intermediate portion of a vertical leg to the frame of the auxiliary article of furniture. Unless these braces were carefully installed and properly aligned, collapsing and extension of the device was difficult. After use, looseness and play developed in the assembly of the prior devices, producing a feeling of insecurity and annoyance in a user of the furniture because of the unsteadiness of the auxiliary article of furniture.

It is to be noted that in the device or hardware for use in furniture construction and forming the subject matter of this application, a beam is provided which cooperates with a folding leg in such manner as to provide support for the auxiliary upholstered section in a desired plane in suitable proximity to the other portions of the article of furniture, the sections being firmly held in desired operative relation until such time as they are purposely folded into a more compact form wherein the auxiliary section is concealed within the main portion of the article of furniture.

The primary object of this invention is to design and provide an improved construction for a supporting device capable of being used with an auxiliary article of furniture (such as an upholstered ottoman, section of mattress, etc.), to foldably associate said auxiliary article with another article of furniture wherein the supporting device is provided with both lateral and longitudinal stability.

An object of this invention is to design and provide a supporting device for use in furniture construction wherein a supporting leg is smoothly operable into collapsed or extended relation by automatic means.

Another object of this invention is to design and provide a supporting device for use in furniture construction of the type described above wherein spaced pivotal connections are provided between a supporting leg and supported beam

2

member whereby lateral movement of the leg with respect to the member is virtually eliminated.

Generally speaking, this invention comprises an improved supporting device for use in furniture construction, as above described, wherein a beam member of U section is adapted to be secured to a frame of an auxiliary article of furniture and a leg of U section is provided with spaced pivotal connections to said member to afford lateral stability. Likewise, the member is provided with spaced pivotal connections to a plate member which is adapted to be secured to the article of furniture to which the auxiliary article is connected and within which the auxiliary article of furniture may be concealed.

Other objects and advantages of this invention will be readily apparent from a consideration of the description and drawings.

20 In the drawings:

Fig. 1 is a side elevational view of a furniture construction embodying this invention and shown in extended relation.

Fig. 2 is a fragmentary enlarged view taken from the plane indicated by line II—II of Fig. 1.

Fig. 3 is an enlarged fragmentary side view partly in section of the construction embodying this invention.

Fig. 4 is a fragmentary sectional view taken in a vertical plane indicated by line IV—IV of Fig. 3.

Fig. 5 is a diagrammatic view illustrating associated articles of furniture in partially folded relation.

Fig. 6 is a diagrammatic view illustrating the associated articles of furniture in completed folded relation and ready for concealment in one of the articles of furniture.

Referring to the drawings, an article of furniture, such as an upholstered chair, generally indicated at 10, may comprise a back member 11 and a main seat cushion 12 supported on a hollow box-like compartment 13 formed in any suitable manner as part of a chair frame. Compartment 13 may be defined by a bottom wall 14 and upstanding vertical side and end walls 15. The main seat cushion 12 includes a frame having a hinged connection 16 to the rear wall 15 of compartment 13.

Compartment 13 is of a size arranged to receive a foldaway ottoman or associated article of furniture generally indicated at 17, said ottoman including an upholstered cushion 18 carried on a rectangular wooden frame 19.

In extended relation (Fig. 1), ottoman 17 is supported by a self-actuating, supporting device

or assembly, generally indicated at 20, which is capable of being completely collapsed when cushion 18 is received within compartment 13. A supporting device 20 may be employed at opposite sides of ottoman 17. Each device 20 includes a longitudinally extending normally horizontal rigid beam member 21 having a web 22 provided with means whereby ottoman or section 17 can be firmly connected thereto; for example, beam 21 may be secured to a bottom surface of frame 19 adjacent inner margins thereof by any suitable means such as wood screws. Integrally formed along longitudinal edges of web 22 are spaced longitudinally extending depending flanges 23 forming with the web a rigid, strong member of generally U-shaped cross-section.

A vertical supporting leg 24 may also be formed of U cross-section and includes spaced walls 25 joined by a transverse wall 26. Upper ends of walls 25 are pivotally connected to the outer ends of flanges 23 by a suitable pin or rivet bolt 27. It should be noted that end portions of walls 25 enclose or overlap adjacent outer end portions of flanges 23 and that spaced aligned pivotal connections 28 are provided through said end portions. The overlapping arrangement of the end portions of walls 25 and flanges 23 provide large bearing surfaces 29 of generally rectangular shape when the leg 24 is in extended relation. End edges of flanges 23 and of web 22 are provided along lines perpendicular to the axis of member 21 and lie in the same plane. The end edges of flanges 23, when the device is in extended relation, abut the inner face of wall 25 and the end edge of web 22 abuts the top edge margin of wall 26. Such an arrangement provides a pivotal mounting having great lateral and longitudinal stability because of the large bearing areas and the abutment of edges of said member 21 with the transverse web of the leg, and movement or play of leg 24 with respect to member 21 is virtually eliminated when in extended relation.

The opposite bottom end of leg 24 may be provided with a suitable convex boss 30 adapted to rest upon a supporting surface without marring. Boss 30 may be integral with wall 26 and spaced from walls 25 to permit reception of the boss between flanges 23 when the leg is collapsed.

A flat plate member 31 of generally rectangular shape is provided with a pair of spaced depending ears 32 receiving therebetween the inner end portion of member 21. A pin or bolt 33 pivotally connects the inner end portions of flanges 23 and ears 32 and provides spaced pivotal connections 34. Each pivotal connection 34 includes enlarged contact surfaces between inner end portions of flanges 23 and depending ears 32. A laterally-stable pivotal mounting is thus afforded.

Plate member 31 is adapted to be secured by suitable wood screws to a wooden frame of the main seat cushion 12 for pivotally connecting the main seat cushion and the ottoman 17.

A self-actuating operating rod or arm 35 is provided for automatically moving leg 24 into collapsed assembled relation with beam member 21 when the ottoman is moved into folded assembled relation with the main seat cushion 12. Rod 35 extends along member 21 in a parallel vertical plane and in diagonal relation to member 21. The outer end of rod 35 is pivotally connected at 36, above and slightly inwardly of pivotal connections 28, to an upstanding extension 37 formed integrally with the inner wall 25 of leg 24. At its opposite end, rod 35 is pivotally

connected at 38, rearwardly and slightly below pivotal connections 34, to a depending flange 39 integrally formed with the inner edge of plate 31. Flange 39 merges with and lies in the same plane as the inner ear 32 and lies virtually in the same plane as extension 37.

When the member 21 and the plate member 31 are in extended horizontal position, a slight gap is provided between the rear edge of wall 22 on member 21 and plate 31. When member 21 is moved slightly upwardly beyond a horizontal relationship with plate member 31, the inner edge of top web 22 may abut the adjacent opposing edge of plate member 31. The supporting leg assembly is thus positively locked against downward movement of pivotal connections 34.

To move ottoman 17 from extended position as indicated in Fig. 1 to a collapsed and concealed position within compartment 13, a force may be suitably applied to ottoman 17 so as to raise or elevate pivotal connections 34 of the ottoman to the main seat cushion 12 while swinging the ottoman toward the cushion 12. The main seat cushion 12 may pivot about hinge point 16. The swinging movement of member 21 toward plate 31 causes the operating arm 35 to exert a turning force about pivotal connections 28 through its pivotal connection 36 to leg 24, causing leg 24 to swing inwardly toward member 21. Fig. 5 illustrates approximately a half-way position of ottoman 17 and seat cushion 12 showing leg 24 in approximately half-way folded relationship with member 21. As the ottoman 17 is further swung toward the bottom of cushion 12, leg 24 receives adjacent portions of flanges 23 of member 21 when the ottoman is in final and in completed folded relation with respect to seat cushion 12. Fig. 6 illustrates ottoman 17 and the seat cushion 12 lying in parallel relationship with the leg assembly completely collapsed and with the ottoman ready to be swung about hinge connection 16 into compartment 13.

To move ottoman 17 from its concealed position in compartment 13 to fully extended relation, the above described operation is reversed. As the seat cushion 12 is swung about its pivotal mounting and ottoman 17 swung outwardly about its pivotal mounting with respect to the seat cushion, operating rod 35 causes leg 24 to move into perpendicular locked relationship with the member 21 when in full extended relation.

While the plate member 31 and beam member 21 have been illustrated as having a pivotal connection 34 immediately adjacent the forward edge margin of seat cushion 12, it is understood that the supporting leg assembly may be moved rearwardly if so desired. Normally the ottoman 17 is provided with a fringe for concealing the leg assembly.

It should be particularly noted that each supporting device includes a rigid beam member and leg of U section. When extended, lateral play, instability, or unsteadiness between member 21 and leg 24 is virtually eliminated because of spaced pivotal connections 28 and the relatively large contact surfaces between end portions of flanges 23 and walls 25. The leg 24 is rigidly and positively held against turning about the pivotal connections 28 beyond perpendicular relation by abutment of end edges of flanges 23 against the transverse connecting wall 26.

It should be particularly noted that each supporting device 20 does not employ side or front diagonal bracing. Each device is capable of being smoothly operated when moving the ottoman.

into either collapsed or extended relation with a seat cushion 12. The construction of the supporting device is not only exceptionally strong but is capable of collapsing into a compact assembly occupying a minimum of space.

Other changes and modifications coming within the scope of the appended claims are embraced thereby.

I claim:

1. A device of the character described for use in furniture construction in combination: a beam member of U cross-section adapted to be secured to an article of furniture with legs of the U section in depending relation when the device is extended; a plate member adapted to be secured to another article of furniture and having spaced depending elements receiving therebetween one end of the beam member; a leg of U section receiving the other end portion of the beam member; spaced pivotal connections between the beam member and leg and between the beam member and plate member; an extension integral with said leg and extending beyond the spaced pivotal connections between the leg and beam member; a depending wall on the plate member lying in the same plane as said extension; and an operating rod pivotally connected to the extension and to the wall of the plate member; end edges of the flanges of said beam member being arranged to abut the adjacent end portion of the web of said leg when said leg is in extended perpendicular relationship to said beam member.

2. A self-actuating supporting device for use in furniture construction including: a rigid beam member having a web and spaced longitudinally extending depending flanges; a rigid leg comprising spaced side walls and a transverse connecting wall, the side walls at one end of said leg overlapping adjacent portions of the depending flanges of said beam member and having aligned pivotal connections with the adjacent end portions of said flanges; a plate member having a pair of depending ears providing spaced pivotal connections to opposite end portions of said flanges; an upstanding extension on one wall of the leg, a depending wall on the plate member merging with one of said ears; an operating arm pivotally mounted at one end to the extension above said spaced pivotal connections of the leg to the beam member and pivotally mounted at

5

its opposite end to the depending wall of the plate member normally behind the spaced pivotal connections of the plate member to the beam member when the leg is in extended relation; the end edges of the flanges on the beam member adjacent the leg abutting the transverse connecting wall on the leg when the device is in extended relation.

10

3. A device of the character described for use in furniture construction in combination: a beam member of U cross-section including a web and depending flanges and adapted to be secured to an article of furniture with the flanges in depending relation when the device is extended; a plate member adapted to be secured to another article of furniture and having spaced depending elements receiving therebetween one end of the beam member; a leg of U section including rearwardly extending spaced side walls and a transverse connecting wall and receiving the other end portion of the beam member; spaced pivotal connections between the beam member and leg and between the beam member and plate member; an extension integral with one side wall of said leg; a depending wall on the plate member lying in the same plane as said extension; an operating rod pivotally connected to the extension and to the depending wall of the plate member; and end edges formed on the flanges and web of the beam member in perpendicular relation to the axis of the beam member and arranged to abut the adjacent portion of the transverse wall on said leg when said leg is in extended relation to hold said leg in perpendicular relation.
